OIL COMBUSTION APPARATUS

Oscar C. Schroeder and Stanley Perry, Chicago,
Ill.; said Perry assignor to Automatic Burner
Corporation, Chicago, Ill., a corporation of
Illinois

Application January 30, 1933, Serial No. 654,356

20 Claims. (Cl. 158—4)

Our primary object is to provide an oil-combustion apparatus of the type in which the combustion of the oil delivered from the center of the hearth takes place generally in the form of a ring at the outer peripheral portion of the hearth, improvements to the end that complete combustion of the fuel will be effected and maximum efficiency obtained.

More specific objects are to provide a hearth of such construction and associate therewith a burner in such a way, that the result above referred to may be effected; to provide, in a structure of the character above referred to and embodying gas-ignition means, for the shielding of the gas flame from the direct blast produced by the burner, without impairing its usefulness for igniting the fuel; to provide for the thorough intermixing of the oil, in vaporized condition, and the air to effect complete combustion relatively close to the hearth; to provide a construction whereby leakage of air through the hearth will be prevented; and other objects as will be clear from the following description.

Referring to the accompanying drawings:

25 Figure 1 is a view in elevation of a furnace embodying our invention and comprising, as an element thereof, an oil-burner assembly certain parts of the structure shown being represented in sectional elevation.

30 Figure 2 is an enlarged broken sectional view in elevation of the ignition means for the burner and a portion of the furnace hearth, the section being taken at the line 2—2 on Fig. 3, and viewed in the direction of the arrow.

35 Figure 3 is a broken plan view of the portion of the hearth shown in Fig. 2 showing the pilots in plan section.

Figure 4 is a developed view in elevation of the portion of the hearth shown in Fig. 3, the hearth being viewed from the interior of the furnace and the view being taken along the line 4—4 on Fig. 3 and viewed in the direction of the arrows.

Fig. 5 is a plan view of my improved hearth ring sections of such shape, number and grouping as to form a hearth ring of one diameter; and

45 Fig. 6, a similar view of the hearth ring sections of such number and grouping as to form a ring of a larger diameter.

Referring to the particular construction shown, 50 9 represents a furnace, shown as of the hot-water-boiler type, having a combustion chamber 10 formed with a hearth portion of refractory material centrally apertured and supported on a centrally apertured plate 11, as for example of 55 metal, carried by the base 12 of the furnace.

The hearth portion shown formed of any suitable refractory material comprises a ring-like base portion 13 having at its outer periphery an upwardly extending ring-like side-wall forming flange 14, a ring 15 superposed on the ring portion 5 13 concentrically therewith but of smaller diameter, and a ring 16 preferably formed of arcuate sections disposed in a circular series and resting on the outer marginal portion of the ring 13 beyond the ring 15 and filling the space between 10 the ring 15 and the lower end portion of the side-wall-forming flange 14.

It may here be said that in the assembling of the parts of the combustion apparatus the oil burner assembly is positioned at the lower end 15 of the combustion chamber 10, and the plate 11 then applied in the position shown. The base portion 13 preferably formed of cement is then cast on the plate, and, if desired, the flange portion 14 cast separately, in which case the 20 one portion last to be cast is cast before the other sets. Thus in either case the base with its flange form a monolithic structure free of joints. After applying to place the sections of the hearth ring 16 cement to form the ring 15 25 is cast on the base portion 13.

The ring 16 comprises an annular base portion 17 the inner periphery of which is of stepped form to provide, at a considerable distance below its upper edge 18, an annular oil-receiving 30 trough, or groove, 19 and a lower inwardly located annular recess 20 presenting an annular shoulder-forming wall 21. The hearth-ring 16 also comprises concentric annular inner and outer series of breaker teeth 22 and 23, respectively, 35 which rise from the base of the member 16 and are disposed outwardly beyond the groove 19. These two series of teeth are shown as spaced apart in a direction radially of the burner-structure, and the outer series of teeth 23 is set in 40 from the circumference of the base member 16 and thus from the side-wall-forming flange 14. The teeth 22 forming the inner series thereof are shown as of greater height than the teeth 23, which is preferred in the case of the larger sizes 45 of combustion apparatus; and the same number of teeth are provided in each series thereof and they are so disposed, as shown, as to be in radial alinement with each other.

The upper face of the base portion 17 contains 50 a series of downwardly tapering radial slots 24 alternating with the teeth 22 and 23 and the ends of which terminate at upwardly and outwardly inclined walls 24a which merge with the upper surface 18 of the base portion 17.

The ring member 16 is recessed at its outer periphery as indicated at 26 and contains, in its upper face, an upwardly opening groove 27 extending tangentially of the ring member 16 from the recess 26 to, and through, the inner periphery of this ring member, this groove, which cuts through certain of the teeth 22 and 23, serving as a channel through which an igniter flame is projected into the space bounded by ring 16 to ignite the fuel as hereinafter described.

The structure also comprises an oil-burner assembly at the central opening in the hearth for projecting radially outwardly and against the inner surface of the ring member 16, atomized oil for the combustion thereof, adjacent the side wall of the combustion chamber as hereinafter described, the flame produced being in the form of a ring.

The oil-burner assembly comprises a neck-ring 28 located in the central hearth-opening and having an annular external flange 29 underlying the hearth, the ring 28 preferably having an extension ring-section 30.

The neck-ring 28 is supported at intervals by pipes 32, as for example four in number, the lower ends of the pipes 32 extending into openings in a base-plate 33. Extending upwardly into the pipes 32 are rods 34 supported on the floor and slidably in the pipes 32, these several parts being held in vertically adjusted position by set-screws 35 on the plate 33 which extend through openings in the pipes 32 and bear at their inner ends against the rods 34.

The construction shown also comprises a vertically disposed electric motor 36 supported on a hollow member 37 arranged concentric with the opening in the neck ring 28, the member 37 being supported on the neck ring 28.

The upper end of the member 37 is formed of a hollow generally frusto-conically shaped portion 43 the open upper extremity of which, is surrounded by a ring 44 located concentrically within in the neck ring 28 in spaced relation to both the portion 43 and neck ring 28.

Supported to extend downwardly into the upper end of the opening in the neck ring 28 but in spaced relation thereto throughout its circumference as shown, is a ring 46 the upper surface of which is so shaped as to present the annular upwardly tapering surface represented at 47.

The armature shaft of the motor 36 is represented at 48 and extends centrally upwardly through the portion 43 of member 37 to an elevation above the neck ring 28.

Secured to the upper end of the shaft 48 are air-forcing and air-distributing means of any desirable construction shown as comprising an inverted shallow, rotatable pan-like member 57 secured to the shaft 48, the rim 58 of the member 57 extending downwardly into the opening in the ring 46. The member 57 contains a series of openings 59 certain of which register with pipes 50 through which the oil, in the operation of the motor 36, discharges, the pipes 50 being shown as projecting outwardly a slight distance through these openings, these means also comprising air-forcing means (not shown) for discharging air outwardly through the openings 59.

In the operation of the burner structure oil supplied to the air-forcing and air-distributing means discharges through the tubes 50 and air flows upwardly through the member 43 and thence discharges outwardly as a blast through the openings 59 in the pan member 57, the oil

and air so discharging impinging against the hearth ring 16.

The burner assembly is mounted in the furnace at such an elevation that the oil discharging from the pipes 50 impinges against the hearth ring 16 substantially in the plane of the base portions of the inner row of teeth 22, viz., in the plane of the upwardly flaring walls of the slots 24.

The installation shown also comprises means for supplying an igniter flame to the hearth 10 through the groove 27, these means which are of the flare-jet type comprising a pilot burner 71 producing a constant flame and a flare-jet burner 72 both shown as formed of vertically disposed pipes closed at their upper ends and located in the recess 26. The flare-jet burner 72 is located at the outer end of the groove 27 and contains an outlet 73 so disposed as shown that the flame, produced by ignition of the gas discharging therefrom, travels through the groove 27 from its outer end, into and through, its inner end to the space within the hearth adjacent the oil trough 19.

The pilot burner 71 is located to one side of the groove 27 between the flare-jet burner 72 and the inner end of the groove 27 and contains a gas-outlet 74 so disposed, as shown, that the flame produced by the gas issuing therefrom extends into the groove 27 crosswise thereof, intersecting the stream of gas issuing from the flare jet 30 burner 72 when the latter is opened to the gas supply as hereinafter described, and impinging against the opposite side wall of the groove 27.

The means shown for controlling the supplying of gas to the burners 71 and 72 may be of any desirable construction such as is commonly in use and preferably of the type operating automatically in the starting of the main burner to supply gas to the flare jet burner only during, and for a few seconds after, the main-burner-starting operation; the means shown comprising a magnetic gas control assembly formed of a casing 75 surmounted by a head 76 containing a passage 77 into which the pipe 78 for supplying gas to the burners 71 and 72 opens, the passage 77 communicating, under the control of a needle valve 79, with a passage 80 connected by a pipe 81 with the pilot-burner pipe 71. The passage 77, which is reduced at its lower end, contains an opening 82 at which it communicates with a pipe 83 leading to the flare-jet-burner pipe 72. Interposed between the inlet pipe 78 and the outlet opening 82 is a valve 84 shown as in the form of a ball on the upper end of a stem 85 pivotally connected at its lower end to the vertically movable core 86 of a solenoid 87 in the casing 75, the coil of which is represented at 88. In accordance with common practice the coil 88 is assembled with suitable electrically controlled devices (not shown) for energizing the coil to raise the core 86 and unseat the valve 84 and thus permit gas to flow to the flare-jet burner 72 during the burner-starting periods to ignite the atomized fuel and air-mixture discharged to the rim of the hearth as above described.

In the starting of the burner the oil discharging to the hearth as hereinafter described is ignited by the gas-flame produced by the ignition means, the groove 27 being so positioned as shown that the igniter flame is projected into the combustion chamber 10 in the direction of rotation of the oil and air delivering means described, viz., in the direction of the arrow in Fig. 3.

As a premise to a description of the particular manner in which the burner functions in connec-

tion with the hearth construction shown, it may be stated that the oil discharging from the pipes 50 is substantially uniformly distributed in a circular substantially horizontal sheet around the 5 main burner, impinging against the hearth ring 16 in the plane of the base portions of the inner row of teeth 22 as above stated, these teeth as also the vertical rear side wall of the oil groove 19 becoming very hot in the continued operation 10 of the burner and thus thoroughly vaporizing the oil.

The air, however, in discharging from the burner through the openings 59 spreads vertically to a slight degree, portions of the blast forcibly 15 impinging against the teeth 22 and passing through the spaces therebetween and other portions thereof sweeping downwardly along the upper surface of the hearth below the plane of the oil stream. The lower portion of the air stream 20 strikes the wall 21 thereby causing the air to be deflected upwardly against the faces of the teeth 22, most of the air passing by, without entering, the oil groove 19 thereby causing a deficiency of 25 oxygen in this groove so that the oil vapors there- 30 in are not combustible to a great degree, which prevents maintenance of a steady flame in the oil groove. A large proportion of the air discharged through the openings 59 sweeps over the top of the teeth 22 into the zone above the teeth 22 and 30 23 and represented generally at 89.

A part of the air which passes between the teeth 22 as stated enters zones represented generally at 90 and 91 and probably most of the oil vaporized in front of the teeth enters these zones and inasmuch as the amount of oil vapor which passes between the fingers into the zones 90 and 91 is far in excess of the amount that can be consumed by the air which enters these zones with the oil vapor, only partial combustion of the oil vapor takes 40 place in zones 90 and 91. As will be understood the air and oil vapor passing through the radial spaces between the teeth expand with resultant decrease in velocity and swirl spirally in the spaces between the teeth 22 and 23 and also the 45 spaces behind the teeth 23 which promotes thorough intermixture of the oil vapor and the air. The velocity of the oil vapor and air entering zones 90 and 91 decreases to such an extent that stable combustion can be established in these 50 zones; however, the partially consumed gases in traveling from the zones of incomplete combustion adjacent the teeth 22 and 23 into zone 89 become mixed with the air flowing into this zone as above stated forming a completely combustible 55 mixture which thereupon burns in this zone.

The feature of forming the hearth ring 16 with the recess 20 affording the wall surface 21 is of advantage inasmuch as the height of such surface is predetermined and fixed in the manufacture of 60 the hearth ring, and reliance is not required to be placed on the workman installing the apparatus in a furnace, to produce the desired height of wall, as in the case of these structures wherein the elevation of the lower exposed edge of such 65 wall is determined by the height to which the cement of the hearth is built up on the wall.

To permit one size and shape of hearth section to be used for the making of hearths of different diameters, the ends of each hearth section are 70 so shaped that their outer edges lie in planes coincident with the radii of the circle described by the hearth ring 16 as represented at 16^a, their inner edge portions being chamfered at 16^b, and the lines of juncture of these edge portions being 75 represented at 16^c. By way of example the points

16^c would be two inches from the outside curved surface 16^d of the section and 7½ inches from the center about which inner and outer arc-surfaces of the section are described and the distance between the points 16^c—16^c is 2 pi or 5 6.28 inches less the necessary clearance for cement joints between adjacent sections, when it is desired to cement the joints between adjacent sections. The inclination of the surfaces 16^b is such that in a hearth of 18" diameter adjacent 10 tile will fit together at the surfaces 16^b as shown in Fig. 5, and by using an additional one of the sections to form a hearth of 20" diameter adjacent tile will fit together at the surfaces 16^a as shown in Fig. 6. This same feature of providing 15 the hearth sections with double inclined ends as above described also applies to smaller and larger hearth sizes than those above referred to, as for example hearths 14" to 16" or 22" to 26" in diameter, in which cases the radius differs accord- 20 ingly so that one size of hearth section will serve for hearths of 14" to 16" diameter and another size for hearths of 22" to 26" diameter.

While we have illustrated and described a particular construction embodying our invention we 25 do not wish to be understood as intending to limit it thereto as the same may be variously modified and altered without departing from the spirit of the invention.

What we claim as new, and desire to secure by 30 Letters Patent, is:

1. In oil combustion apparatus, the combination of a combustion chamber having a hearth with a raised portion adjacent its periphery and having a surrounding wall structure, and means at 35 the center of said hearth and extending above the latter for projecting finely divided oil and air against the raised portion of said hearth, said raised portion comprising an annular series of breaker teeth spaced from the surrounding wall 40 structure to provide a combustion space outwardly beyond said teeth with which the spaces between the teeth communicate the side walls of the spaces between the teeth at the bottom portions thereof converging downwardly to produce 45 substantially V-shaped spaces and said means being so positioned as to discharge the oil against the bases of said teeth and into said substantially V-shaped spaces.

2. In oil combustion apparatus, the combination 50 of a combustion chamber having a hearth with a raised portion adjacent its periphery and having a surrounding wall structure, and means at the center of the hearth and extending above the latter for projecting finely divided oil and air 55 against said raised portion, said raised portion comprising inner and outer rows of breaker teeth the rows of teeth being spaced apart and the teeth of the outer row spaced from the surrounding wall structure to provide a combustion space 60 between the outer row of teeth and said wall structure and with which the spaces between the teeth of said outer row communicate, the teeth of said rows being in substantial radial alinement.

3. In oil combustion apparatus, the combination 65 of a combustion chamber having a hearth with a raised portion adjacent its periphery and having a surrounding wall structure, and means at the center of the hearth and extending above the latter for projecting finely divided oil and 70 air against said raised portion, said raised portion comprising inner and outer rows of breaker teeth the rows of teeth being spaced apart and the teeth of the outer row spaced from the surrounding wall structure to provide a combustion 75

space between the outer row of teeth and said wall structure and with which the spaces between the teeth of said outer row communicate.

4. In oil combustion apparatus, the combination of a combustion chamber having a hearth with a raised portion adjacent its periphery and having a surrounding wall structure, and means at the center of the hearth and extending above the latter for projecting finely divided oil and air against said raised portion, said raised portion comprising inner and outer rows of breaker teeth the rows of teeth being spaced apart and the teeth of the outer row spaced from the surrounding wall structure to provide a combustion space between the outer row of teeth and said wall structure and with which the spaces between the teeth of said outer row communicate, the teeth of the inner row extending above the teeth of the outer row.

5. A hearth ring comprising sections of arcuate form, those portions of the end surfaces of the sections adjacent the outer side of the hearth ring being on radii of the circle including the outer edge of the section and the portions adjacent the inner side being chamfered to extend at an angle to said portions of the end surfaces which are adjacent the outer side of the hearth ring.

6. In combustion apparatus, the combination of a furnace structure, a burner assembly located at the bottom of said structure substantially centrally thereof and a hearth for the bottom of said furnace structure comprising a base member having a central opening in which the burner assembly is positioned, said base member having an endless upwardly extending flange adjacent its outer periphery, the inner surface of said flange being circular and substantially concentric with the opening in said base member, said base member with its flange filling the space between said burner assembly and the side wall of the furnace structure and conforming to the latter, a hearth ring formed of separate end to end disposed sections placed in superposed position on said base member and against the inner side of said flange, and a ring on said base member completely spanning the space between said hearth ring and said burner assembly.

7. In combustion apparatus, the combination of a furnace structure comprising an upwardly extending wall, a hearth therein having a raised portion adjacent its periphery, means at the center of said hearth and extending above the latter for projecting air and finely divided oil laterally, said raised portion having an angularly disposed channel opening through the inner face of said raised portion, and ignition means the flame from which extends forwardly along said channel, said last-named means being located between said raised portion and the wall of said furnace structure and subjected to the heat of burning gases in the furnace outwardly beyond the inner face of said raised portion.

8. In combustion apparatus, the combination of a furnace structure comprising an upwardly extending wall, a hearth therein having a raised portion adjacent its periphery, the upper portion of the outer face of said raised portion being spaced from the wall of said furnace structure, means at the center of said hearth and extending above the latter for projecting air and finely divided oil laterally, said raised portion having an angularly disposed channel opening through a side of said raised portion facing said means, and ignition means the flame from which ex-

tends inwardly along said channel, said last-named means being located between the upper portion of the outer face of said raised portion and the wall of said furnace structure.

9. In oil combustion apparatus, the combination of a combustion chamber having a hearth and presenting an impact wall, rotary means at the center of said hearth and extending above said hearth for projecting air and finely divided oil laterally against said impact wall, the raised portion of said hearth having an angularly disposed channel opening into the combustion chamber through said impact wall, and ignition means the flame from which extends inwardly along said channel, said channel being so disposed that the ignition flame discharges into said combustion chamber generally in the direction of rotation of said first-named means.

10. In oil combustion apparatus, the combination of a combustion chamber having a hearth with a raised portion adjacent its periphery presenting upwardly extending teeth spaced apart around the combustion chamber, means at the center of said hearth and extending above the latter for projecting air and finely divided oil laterally, the raised portion of said hearth having an angularly disposed channel intersecting certain of said teeth and opening into the combustion chamber, and ignition means the flame from which extends inwardly along said channel, the radial spaces between the teeth intersected by said channel being substantially of the same width as the spaces between the remainder of said teeth to insure uniformity of performance around the hearth.

11. In oil combustion apparatus, the combination of a combustion chamber having a hearth and a surrounding wall structure, said hearth having a raised portion adjacent its periphery and comprising a base portion and inner and outer rows of teeth rising therefrom, the rows of teeth being spaced apart and the teeth of the outer row spaced from the surrounding wall structure to provide a combustion space between the outer row of teeth and said wall structure and with which the spaces between the teeth of said outer row communicate, the spaces between the teeth of each row thereof extending below the upper surface of said base portion and said upper surface containing radial grooves alining, and communicating, with said spaces, and means at the center of said hearth and extending above the latter for projecting air and finely divided oil laterally against said raised portion.

12. In combustion apparatus, the combination of a furnace structure, a burner assembly located at the bottom of said structure substantially centrally thereof and a hearth for the bottom of said furnace structure comprising a base member having a central opening in which the burner assembly is positioned, said base member having an endless upwardly extending flange adjacent its outer periphery, in sealed relationship thereto, and a hearth ring on said base member within the confines of said flange, said hearth ring at the upper portion being spaced from said flange and forming, with said flange, walls of a combustion space, said flange extending above the top of said hearth ring.

13. In combustion apparatus, the combination of a furnace structure, a burner assembly located at the bottom of said structure substantially centrally thereof and a hearth for the bottom of said furnace structure comprising a base member having a central opening in which the burner

assembly is positioned, said base member having an endless upwardly extending flange adjacent its outer periphery, the inner surface of said flange being circular and substantially concentric with the opening in said base member, said base member with its flange filling the space between said burner assembly and the side wall of the furnace structure and conforming to the latter, and a hearth ring placed in superposed position on said base member and against the inner side of said flange, the upper portion of said hearth ring being spaced from said flange and forming, with said flange, walls of a combustion space, said flange extending above the top of said hearth ring.

14. A hearth element formed of a base portion and inner and outer rows of teeth rising therefrom, the rows of teeth being spaced apart with the spaces between the teeth of each row opening to the inner and outer faces of the teeth and the outer side of said base portion extending outwardly beyond the outer faces of the outer row of teeth.

15. In oil combustion apparatus, the combination of a combustion chamber having a hearth with a raised portion adjacent its periphery, and means at the center of the hearth and extending above the latter for projecting finely divided oil and air against said raised portion, said raised portion comprising inner and outer rows of breaker teeth the rows of teeth being spaced apart, and the teeth of the inner row thereof extending above the teeth of the outer row.

16. In oil combustion apparatus, the combination of a combustion chamber having a hearth with a raised portion adjacent its periphery and having a surrounding wall structure, and means at the center of the hearth and extending above the latter for projecting finely divided oil and air against said raised portion, said raised portion comprising a base portion and inner and outer rows of breaker teeth rising from said base portion, the teeth of said rows being in substantial radial alinement, the rows of teeth being spaced apart and the teeth of the outer row spaced from the surrounding wall structure to provide a combustion space between the outer row of teeth and said wall structure and with which the spaces between the teeth of said outer row communicate, and the upper surface of said base member having substantially radial grooves open at their inner ends and extending from the inner faces of the teeth of the inner row beyond the corresponding faces of the teeth of the outer row and located at the bottoms of the spaces between adjacent teeth of both of said rows.

17. A hearth element formed of a base portion and inner and outer rows of teeth rising therefrom, the rows of teeth being spaced apart with the spaces between the teeth of each row opening to the inner and outer faces of the teeth and the outer side of said base portion extending outwardly beyond the outer faces of the outer row of teeth, said element having a portion presenting a substantially vertical inwardly facing curved

wall surface located between the innermost surface of said base portion and the inner surfaces of the inner row of teeth and extending to an elevation below the upper ends of said last referred to teeth.

18. In oil combustion apparatus, the combination of a combustion chamber having a hearth with a raised portion adjacent its periphery and having a surrounding wall structure, and means at the center of the hearth and extending above the latter for projecting finely divided oil and air against said raised portion, said raised portion comprising inner and outer rows of breaker teeth the rows of teeth being spaced apart and the teeth of the outer row spaced from the surrounding wall structure to provide a combustion space between the outer row of teeth and said wall structure and with which the spaces between the teeth of said outer row communicate, the teeth of said rows being in substantial radial alinement and the side walls of the spaces between the teeth of the inner row at the bottoms thereof converging downwardly to produce substantially V-shaped spaces, said means being so positioned as to discharge the oil against the bases of said teeth and into said substantially V-shaped spaces.

19. In oil combustion apparatus, the combination of a combustion chamber having a hearth with a raised portion adjacent its periphery and having a surrounding wall structure, and means at the center of the hearth and extending above the latter for projecting finely divided oil and air against said raised portion, said raised portion comprising inner and outer rows of breaker teeth the rows of teeth being spaced apart and the teeth of the outer row spaced from the surrounding wall structure to provide a combustion space between the outer row of teeth and said wall structure and with which the spaces between the teeth of said outer row communicate, the teeth of said rows being in substantial radial alinement, and the side walls of the spaces between the teeth of each of said rows at the bottoms thereof converging downwardly to produce substantially V-shaped spaces, said means being so positioned as to discharge the oil against the bases of said teeth and into said substantially V-shaped spaces.

20. In oil combustion apparatus, the combination of a combustion chamber having a hearth with a raised portion adjacent its periphery, means at the center of said hearth and extending above the latter for projecting finely divided oil and air laterally, the raised portion of said hearth having a tangentially disposed upwardly opening channel opening into the combustion chamber, said hearth having a recess at its outer periphery which recess opens into the outer end of said channel, and ignition means in said recess for directing an ignition flame inwardly along said channel, for the purpose set forth.

OSCAR C. SCHROEDER.
STANLEY PERRY.
